UNITED STATES PATENT OFFICE

160,910

KITE

Claude L. Wolford, Los Angeles, Calif.

Application July 19, 1949, Serial No. 3,991

Term of patent 14 years

(Cl. D34—15)

To all whom it may concern:

Be it known that I, Claude L. Wolford, a citizen of the United States, residing at Los Angeles, in the county of Los Angeles and State of California, have invented a new, original, and ornamental Design for a Kite, of which the following is a specification, reference being had to the accompanying drawing, forming part thereof.

In the drawing:

Fig. 1 is a perspective view of the kite, showing my new design;

Fig. 2 is a top plan; and

Fig. 3 is an end elevation.

I claim:

The ornamental design for a kite, as shown.

CLAUDE L. WOLFORD.
